(57) **CLAIM**

The ornamental design for a base for a wheeled chair, as shown and described.

DESCRIPTION

FIG. 1 is a top, front, right side perspective view showing a base for a wheeled chair showing our new design;

FIG. 2 is a front elevational view thereof;

FIG. 3 is a left side elevational view thereof;

FIG. 4 is a top plan view thereof;

FIG. 5 is a bottom plan view thereof; and,

FIG. 6 is a rear elevational view thereof.

The dotted lines are for environment only and are not part of the claimed design.
